UNITED STATES PATENT OFFICE

101,595

DESIGN FOR BOOK PAPER OR SIMILAR ARTICLE

James T. Cronk, Granby, Mass., assignor to Hampden Glazed Paper & Card Co., Holyoke,
Mass., a corporation of Massachusetts

Application August 27, 1936, Serial No. 64,594

Term of patent 3½ years

To all whom it may concern:

Be it known that I, James T. Cronk, a citizen of the United States, residing at Granby, in the county of Hampshire and State of Massachusetts, have invented a new, original, and ornamental Design for Book Paper or Similar Article, of which the following is a specification, reference being had to the accompanying drawing, forming a part thereof.

The figure is a view of a piece of book paper or similar article embodying my new and ornamental design.

I claim:

The ornamental design for book paper or similar article as shown.

JAMES T. CRONK.
